UNITED STATES PATENT OFFICE.

IRA A. KNECHT, OF NAZARETH, PENNSYLVANIA.

TUBE-MILL FOR CEMENT, STONES, AND THE LIKE.

No. 927,054.

Specification of Letters Patent.

Patented July 6, 1909.

Application filed March 26, 1908. Serial No. 423,398.

To all whom it may concern:

Be it known that I, IRA A. KNECHT, a citizen of the United States, residing at Nazareth, in the county of Northampton and State of Pennsylvania, have invented certain new and useful Improvements in Tube-Mills for Cement, Stones, and the Like; and I do declare the following to be a full, clear, and exact description of the invention, such as will enable others skilled in the art to which it appertains to make and use the same.

This invention relates to tube mills for cement, graphite, blue-stone, rocks and the like, and to attachments for mills of this kind.

The object of this invention is to provide in a tube mill means for quickly and economically removing material which has been ground fine enough from the material which has not been ground fine enough.

Another object is to provide in a mill of this kind means for either raising or lowering the temperature of the material to be ground as desired.

Another object is to provide a false head in the main cylinder of the mill to prevent the entrance of the grinding pebbles into the feed mechanism.

For these and still other objects which will appear as the nature of the invention is disclosed, my invention consists of certain novel arrangements and combinations of parts of which the herein-described machine is one of many possible embodiments.

In the accompanying drawings, forming a part of this specification, in which like reference characters refer to like parts throughout the several views and which are for illustrative purposes only and therefore not drawn to any particular scale, Figure 1 is a longitudinal sectional view of a tube mill constructed with parts showing an embodiment of my invention; Fig. 2 is a top plan view of the same; Fig. 3 is an elevation showing the forward face of the false head; Fig. 4 is a view of the rear face of the false head; Fig. 5 is a sectional view taken on the line 5—5 of Fig. 3; Fig. 6 is a view of the forward face of the false head showing the air pipe attached; Fig. 7 is a detailed sectional view taken on the line 7—7 of Fig. 6; Fig. 8 is a sectional view taken on the line 8—8 of Fig. 2; and Fig. 9 is a perspective view of a portion of the false head.

Referring more particularly to the draw-

ings, I show a tube mill comprising a main cylinder 1 having trunnion bearings 2 and 3 supported on suitable foundations 4, having a feed mechanism generally indicated by reference numeral 5 and a discharge mechanism generally indicated by reference numeral 6. These parts may be of any ordinary construction but for the purpose of illustrating the present invention, I have shown them as herein described.

The cylinder 1 is provided at its forward or feed end with a forward head 7 secured as by bolts 8 to a flange 9 riveted or otherwise secured to the forward end of the cylinder 1; the rear or discharge end of the cylinder is provided with a rear head 10 similarly secured to the cylinder and provided with a gear 11 adapted to intermesh with a similar gear 12 on the counter shaft 13 to which power may be applied for rotating the machine.

The cylinder 1 is provided with a suitable side lining 14 and an end lining 15 whereby the same is protected from the action of the grinding pebbles used therein. In the forward or feed end of the cylinder I provide a false head 16 rigidly secured to the head 7 by means of bolts 17 and held spaced from said head by means of bosses 18 as clearly shown. Rigidly secured to said false head 16 are a plurality of buckets 19 substantially triangular in cross section as shown in Fig. 7 and having the forward end 20 open and the rear end 21 closed. The outer or flat side 22 of the buckets 19 lie substantially flush with the lining of the cylinder, as herein shown. The cylinder lining is made slightly thicker adjacent the buckets as at 23, but this construction is, of course, immaterial. The side of the bucket 19 which is formed by the false head 16 is provided with a plurality of radially extending slots 24, said slots being tapering as shown in Fig. 5; the forward or entrance opening 25 of said slots being narrower than the discharge side 26 to prevent the material passing therethrough from being wedged therein. The feed mechanism 5 is supported upon a supporting block 27 secured in the foundation 4. The feed mechanism 5 comprises a stationary supporting portion 28 to which is securely fastened in any convenient manner the feed tube 29. Passing co-axial of the tube 29 is the feed shaft 30 which is held in correct position by rods in the alined bearings 31 and 32 rigidly

supported on the stationary part 28. The shaft 30 carries the feed screw 33 in the tube 29 and also carries between the bearings 31 and 32 a gear wheel 34 adapted to intermesh 5 with the spur-gear 35 on the counter shaft 36; said counter shaft carries another spur-gear 37 which intermeshes with the larger gear 38 rigidly secured to the trunnion bearing tube. The counter shaft 36 may be di- 10 vided and provided with any convenient form of clutch as 38'. The outer end of the counter shaft 36 may be provided with an eccentric pin 39 carrying a link 40 adapted to oscillate the arm 41 whereby the shaking 15 hopper may be actuated.

The forward face of the false head 16 is provided with an annular groove 43 placed concentric with said false head within the circle determined by the buckets 19. The rear portion of said groove is cut through to form slots 44 but connecting portions 45 are left to support the portion of said false head within the circle determined by said groove.

It will be noticed that when the radially extending slots 24 are at their highest point of movement, the uppermost slot 44 is a convenient distance below said radially extending slots. Slidably received in the upper part of said groove 43 is the arc-shaped pipe 46 rigidly and immovably supported at the discharge end 47 of the tube 29 by means of the braces 48 and the pipes 49. The pipes 49 communicate with the arc-shaped pipe 46 and extend through longitudinal recesses 50 in opposite sides of the tube 29. Near the entrance end of said tube said pipes 49 branch outwardly and then converge as at 51 and join in a single pipe 52 which is connected to some source of supply of compressed air. This source of compressed air is not shown as it forms no part of the present invention and any form of air compressing means desired may be used.

The diagonally upwardly extending portion 53 of the pipe 49 together with the braces 48 form an efficient supporting means whereby the arc-shaped pipe 46 is held firmly in position in the annular groove 43 in such a way that said arc-shaped pipe will not bear frictionally against the sides of said annular groove. The pipe 46 is made tapering in cross-section to conform with the shape of the slot 43 and is provided with openings or orifices 54 pointing toward the discharge end 55 of the cylinder and registering with the slots 44.

The rear end of the cylinder 1 is provided with a perforated diaphragm 55 which may be supported between the discharge passage 60 block 56 and the clamping plate 57 and securely clamped together against the cylinder head by means of bolts 58; the discharge trunnion bearing 3 is provided with a cylindrical screen 59 adapted to permit the material of the right fineness to pass down

through the main discharge hopper 60 to pass along the coarse material and empty through the small discharge 61.

The cylinder 1 is provided with a man hole 62 by means of which access may be gained to the interior thereof for relining and repairs: the false head 16 is provided with a removable plate 63 by means of which access may be gained to the space between said plate and cylinder head 7. The false head 16 acts to prevent any accidental entrance of the pebbles in the cylinder 1 into the feed tube 29, therefore it is possible to carry a larger quantity of pebbles in the drum in my machine than in other makes, the operation of the machine not being interfered with when the upper level of the pebbles is as high as indicated at 64 in Fig. 1.

The operation of my device is as follows:—
The rotation of the cylinder 1 causes the rotation of the feed screw 30 and the material to be ground is forced into the space between the head 16 and the head 7 where it falls down upon the lining 22. The cylinder rotates in such a direction that the open end of the bucket 19 leads the closed end thereof and said bucket scoops up a quantity of said material; as the bucket nears the upper part of the cylinder its position becomes reverse and the slanting side of said bucket is placed to the lower side thereof, thus forcing the material in the bucket toward the slots 24; the material then falls downwardly among the pebbles in the cylinder. The material in thus falling must pass in front of the opening 54 in the arc-shaped pipe and suitable air pressure being applied in said pipe a strong draft is created which drives away the particles of the material which may be already as fine as desired. The material after falling down among the pebbles is ground and re-ground by the movement of the pebbles against each other and the lining of the cylinder as the cylinder rotates. The rotation of the cylinder continually turning over the material therein causes different particles of material to be exposed to the air blast from the opening 54 and the air blast is of such an intensity that it blows on through the cylinder any material that has been ground fine enough.

It is of course obvious that the air blast is stronger near the opening 54 than it is near the discharge end of the cylinder. This causes particles of the material to be blown away from the forward end of the cylinder and deposited nearer the discharge end of the cylinder where they remain until they have been ground fine enough to be still further advanced by the gradually weakening air blast. In this way when the material first leaves the slots 24 the coarsest material is deposited nearer the feed end of the cylinder and the finest material is deposited near the discharge end of the 130

cylinder, the various grades ranging from coarsest to finest are deposited along the cylinder from end to end. It will thus be seen that the material on entrance into the cylinder is automatically deposited at the position where it must necessarily receive the required amount of grinding before it reaches the discharge end of the cylinder. The material which is sufficiently fine on its entrance into the cylinder is immediately carried out of said cylinder without any further grinding. The advantages of this arrangement are obvious as the material is never re-ground after it has been ground fine enough but is immediately removed from the machine and the material which requires least grinding stays in the cylinder the shortest length of time. This so increases the capacity of the grinding mill that it has been found that a mill having a cylinder about 5 or 6 feet deep in diameter will grind as much as six barrels per hour more than a similar mill not fitted with the air blast attachment.

Another object of this machine is that by furnishing a hot air blast high lime may be hydrated to its commercial condition, and low lime can be manipulated at all times by using cold air to give the greatest grinding capacity. By using cold air longer life is given to the pebbles because the pebbles are kept cool and are thus prevented from scaling and cracking.

The grinding capacity is increased by the continual separation of the finished from the unfinished product, thus giving the mill the full work on the unfinished product at all times instead of on the finished and unfinished as heretofore. The addition of the false head gives a greater pebble capacity for the mill and at the same time insures less repairs to the shaft, the feed tube and feed screws. It is of course obvious that the advantages of my device greatly decrease the number of horse power necessary to be used in operating the same. My device may be adapted to any of the ordinary mills of this kind now on the market.

Having thus described my invention, what I claim as new and desire to secure by Letters-Patent, is:

1. In a tube mill, a rotary cylinder, a false head in one end of said cylinder, said head having formed therein feed slots arranged in series at intervals around said head, a series of feed buckets arranged on said head opposite each of said series of feed slots

whereby the material entering the end of said cylinder is fed through said slots to the main body of the cylinder, means to feed the material into said end of the cylinder in position to be taken up by said buckets, and means whereby a blast of air is forced through the material as it passes through said slots from said buckets.

65

2. In a tube mill, a rotating cylinder having a false head near its forward end, said head having openings therein, a feed tube for said cylinder and means to conduct an air blast to and to discharge the same through certain of said openings and means connected to said false head to feed material through the other of said openings.

70

3. In a tube mill, a false head having radial openings therein, buckets on the forward face of said false head, covering said radial openings, an annular groove having therein slots passing through said head, and means to pass an air blast through said last named slots and means to feed material to be ground to said buckets.

75

4. In combination, a rotating cylinder having trunnion bearings, supports for said trunnion bearings, means to rotate said cylinder, a stationary feed tube projecting into the forward end of one of said trunnion bearings, a feed screw in said tube, means between said feed screw and said cylinder whereby said cylinder causes said feed screw to rotate, a false head near the forward end of said cylinder radially extending slots near the periphery of said false head, triangular buckets having a single open end secured to said false head covering said radially extending slots, said false head being provided with an annular groove between said buckets and the center of said false head, said buckets being provided with a slanting side on the side nearer the center of said cross head, an arc-shaped pipe having openings pointing toward the discharge end of said cylinder, braces connecting said arc-shaped pipe with said feed tube, said feed tube being provided with longitudinal recesses, an air pipe passing through said recesses and connecting with said arc-shaped pipe and means to hold said false head in said cylinder.
